[57] **ABSTRACT**

A strikeoff rod comprising an elongated hollow member having two walls intersecting generally at right angles to each other. Each of said walls has a beveled portion sloping inwardly starting on a line parallel to but spaced from the intersection of said walls. The extremities of said walls are remote from said intersection, and are connected by an undulant wall.

STRIKEOFF ROD

The tool of this invention is designed especially for use in the cement or concrete finishing trade. A wide variety of such tools are available and are used to level off freshly poured concrete to the same elevation as the top of the forms or screeds between which the concrete is poured. In the trade, such tools are known as "strikeoff rods" and the present invention has been so entitled.

After the wet concrete is poured, the strikeoff rod is placed as a bridge between the two forms and is then dragged lengthwise of the forms with any excess of concrete being removed ahead of the tool, thus leaving the required slab thickness between the forms. This operation is normally performed by two men, one on each end of the strikeoff rod.

The slab to be leveled will range in width from 2 or 3 feet to more than 20 feet and since the screed must exceed in length the width of the slab to be leveled, there arises a rather complicated problem in providing a strikeoff rod which will combine, in the greater lengths, the qualities of rigidity and light weight.

An object of this invention is to provide a strikeoff rod which will combine the qualities of corrosion resistance, light weight and rigidity transverse its length.

It is a further object of this invention to provide a strikeoff rod as aforesaid so designed as to afford comfortable handgrips for the operator.

It is a further object of this invention to provide a strikeoff rod as aforesaid which may be reversed to operate in either direction lengthwise of the supporting forms merely by turning the same through 90°.

The above and other objects will be made clear from the following detailed description taken in connection with the annexed drawing, in which:

FIG. 1 is a perspective view of the improved strikeoff rod with one of its active faces in the foreground;

FIG. 2 is a section on the line 2—2 of FIG. 1; and

FIG. 3 is a perspective view taken from the opposite side of FIG. 1.

As best seen in FIG. 2, the rod of this invention is a seamless hollow structure, preferably extruded of aluminum or magnesium or alloys of aluminum and/or magnesium, but in any case of lightweight metal. It has an active face 10 intersecting at right angles, a second active face 12. A dotted line 14 has been drawn in FIG. 2 to illustrate the relationship to the face 12 to the top of the concrete forms and in use the device shown in FIG. 2 travels from right to left on its initial leveling operation with excess concrete collecting against the face 10 and being forced into depressions in the freshly poured slab.

It will be noted that the faces 10 and 12 intersect along the line 16. It will further be noted that somewhat to the rear of the line 16 the face 12 is joined by an auxiliary planar face 12' which is slightly inclined to the face 12, the angularity being in

the general order of 2° to 5°. The face 10 is provided with a similarly inclined portion 10'.

A planar section 18 adjoins the margin of the section 10' while a similar planar section 20 adjoins the margin of the section 12'. The extremities of the sections 18 and 20 are joined each by concave inwardly directed sections respectively designated 22 and 24. The sections 22 and 24 are joined by an inwardly directed generally semicylindrical section 26.

With the device of FIG. 2 and advancing from right to left,

10 as viewed in that figure, the operators (one at each end of the strikeoff rod) will exert pressure against the surfaces 22 and 24 primarily in the right to left direction to ensure that the surface 12 remains parallel to the line 14. This is the roughing-out

15 pass. At the end of the pass, if it is desired to provide the freshly poured slab with an even smoother surface, the device is rotated counterclockwise around the line 16 to bring the surface 10 parallel to the line 14 and a pass is then made from left to right. In this case, however, the operators exert strong

20 downward pressure against the surface 22 to bring the surface 10' parallel to the line 14 with the surface 10 angled slightly upwardly from the surface 14. This has the effect of pressing downwardly on any raised portions of the freshly poured slab and produce a leveling effect with excess material passing under the surface 10' rather than collecting in front of the surface 12.

25 To prevent concrete entering and building up in the hollow tubular structure and thereby increasing the overall weight, it may be desirable, as best seen in FIG. 3, to provide each end of the structure with a cover plate 30 shaped to conform to the

30 cross section of the tubular structure and secured by welding, brazing or any other suitable means.

35 While certain specific structural details have been illustrated herein, no doubt various structural modifications will occur to anyone skilled in the art who may peruse this disclosure. Accordingly, the invention is not to be limited to the precise details disclosed.

What is claimed is:

1. A strikeoff rod for smoothing freshly poured concrete, said rod comprising: an elongated, tubular member of uniform 40 cross section throughout its length, said member having two planar faces integrally intersecting at right angles to each other, the extremities of said faces being integrally joined by an undulant wall, said wall having outwardly convex contours adjacent said surfaces and an inwardly concave portion joining said convex contours, said planar faces being longitudinally divided substantially equally to form planar portions inwardly inclined relative to the face of which they form a part.

45 2. The device of claim 1, including cover plates secured at each end of said rod to close said tubular member, said plates being contoured to conform to the cross section of said member.
